UNITED STATES PATENT OFFICE

124,716

DESIGN FOR A NOZZLE FOR BATTERY TESTERS OR THE LIKE

Leo Edelmann, Chicago, Ill.

Application May 23, 1940, Serial No. 92,546

Term of patent 14 years

To all whom it may concern:

Be it known that I, Leo Edelmann, a citizen of the United States, residing at Chicago, in the county of Cook and State of Illinois, have invented a new, original, and ornamental Design for a Nozzle for Battery Testers or the like, of which the following is a specification, reference being had to the accompanying drawing forming part thereof, and in which:

Figure 1 is a perspective view of a nozzle for battery testers, showing my design.

Fig. 2 is an end view looking at the upper end.

Fig. 3 is a bottom end view.

I claim:

The ornamental design for a nozzle for battery testers or the like, as shown.

LEO EDELMANN.
